UNITED STATES PATENT OFFICE.

GEORGE E. CUTLER, OF MOUNT VERNON, NEW YORK.

SPRING.

1,218,063.

Specification of Letters Patent.

Patented Mar. 6, 1917.

Application filed November 7, 1914, Serial No. 870,845. Renewed August 23, 1916. Serial No. 116,533.

To all whom it may concern:

Be it known that I, GEORGE E. CUTLER, a citizen of the United States, residing at Mount Vernon, in the county of Westchester and State of New York, have invented 5 certain new and useful Improvements in Springs, of which the following is a specification, reference being had to the accompanying drawings.

10 This invention relates to certain improvements in springs, and an object of the invention is to provide novel and improved means whereby the tension of the spring may be increased in accordance with the increase 15 of the load supported by the spring whereby a maximum of efficiency may be obtained.

Furthermore, it is an object of the invention to provide a spring normally at its 20 minimum of tension and having coacting therewith novel and improved means whereby the tension of the spring may be increased with convenience and facility in accordance with the requirements of practice.

25 The invention consists in the details of construction and in the combination and arrangement of the several parts of my improved spring whereby certain important advantages are attained and the device is rendered simpler, less expensive and otherwise 30 more convenient and advantageous for use, all as will be hereinafter more fully set forth.

The novel features of the invention will 35 be carefully defined in the appended claims.

In order that my invention may be the better understood, I will now proceed to describe the same with reference to the accompanying drawings, wherein—

40 Figure 1 is a fragmentary elevational view illustrating somewhat diagrammatically an embodiment of my invention employed in connection with a semi-elliptical spring;

45 Fig. 2 is a view somewhat similar to Fig. 1, but showing an embodiment of my invention employed in connection with a three-quarter elliptical spring; and

50 Fig. 3 is a view, partly in elevation and partly in section, of a three-quarter elliptical spring including a scroll having a further embodiment of my invention applied thereto.

55 As disclosed in the accompanying drawings, 1 denotes a front axle of a vehicle and 2 a load receiving body. Interposed between

the axle 1 and the body 2 in a conventional manner is the semi-elliptical spring 3, the opposite extremities 4 of which being disposed in substantial parallelism with the axle 1.

Suitably supported by the axle 1 is the shaft 4 having its opposite extremities 5 reversely threaded, the threads of such extremities being disposed on the same pitch. The threaded extremities 5 are disposed through and operatively engaged with the blocks or fulcrums 6 adapted to slide upon the axle 1 and having their upper surfaces 7 crowned and adapted for engagement with the under surface of the portions 4 of the spring 3. It will be readily perceived that upon axial rotation of the shaft 4, the blocks or fulcrums 6 will be caused to move in unison but in reverse directions. While any means may be employed which will operate with facility and convenience for imparting the requisite axial rotation to the shaft 4, I herein disclose a vertically disposed shaft 8 operatively engaged with the shaft 4 through the medium of the conventional beveled gears 9 while the intermediate portion of the shaft 8 is provided with an operating means 10, herein disclosed as a conventional hand wheel.

The spring 3 is normally of a tension to properly compensate for or resist the minimum of load afforded by the load receiving body 2 and the blocks or fulcrums 6 are normally adjusted out of contact with the extremities of the spring 3. It will be self-evident that as the load carried by the load receiving body 2 increases, it is only necessary to impart such axial rotation to the shaft 4 as to cause the blocks or fulcrums 6 to move outwardly to properly increase the tension of the spring 3 and in order that the tension of the spring may be readily determined, I find it of advantage to employ an indicator 11 of conventional construction and herein disclosed as operatively engaged with the shaft 8.

The form of invention disclosed in Fig. 2 is substantially identical with that set forth in Fig. 1, except that the spring 3^a is of a three-quarter elliptical type having the outer extremities 12 thereof disposed in parallelism, while the inner extremity 14 of the lower section of the spring is disposed in substantial parallelism with the frame 1^a. Interposed between the extremities 12 and the extremity 14 and the adjacent portion

of the frame 1^a are the sliding blocks or fulcrums 6^a adapted to operate in a manner as has been set forth relative to the blocks or fulcrums 6. These blocks or fulcrums 6^a are herein disclosed as operatively engaged with the reversely threaded portions 5^a of the shaft 4^a which is adapted to be rotated in any desired manner. As disclosed in Fig. 3, the spring 3^b is also of a three-quarter elliptical type but has the outer extremity of its upper section disposed on a depending scroll 15, and coacting with the inner portion of such scroll 15 is the rocking or swinging fulcrum 16 pivotally supported, as at 17, at the junction of the upper and lower sections of the spring 3^b. The rocking or swinging fulcrum 16 is fixedly secured to the connecting pin or bolt 17, and it will be readily perceived that upon imparting the requisite rocking movement to the fulcrum 16, the tension of the spring 3^b may be controlled in accordance with the necessities of practice. As herein disclosed, the pin or bolt 17 is provided with a rock arm 18 adapted to be engaged by any suitable means for imparting the requisite movement thereto.

From the foregoing description, it is thought to be obvious that a spring constructed in accordance with my invention is of an extremely simple and comparatively inexpensive nature and is particularly well adapted for use by reason of the convenience and facility with which it may be assembled, and it will also be obvious that my invention

is susceptible of some change and modification without material departure from the principles and spirit thereof and for this reason I do not wish to be understood as limiting myself to the precise arrangement and formation of the several parts herein shown in carrying out my invention in practice.

What I claim is:

1. The combination with a support, a load receiving body, and a spring interposed therebetween; of means for adjusting the tension of the spring in accordance with the load carried by the load receiving body, and means under control of the adjusting means for indicating the tension of the spring under the influence of the first named means.

2. The combination with a support, a load receiving body, and a spring interposed therebetween and normally under a minimum of tension; of movable means coacting with the spring for increasing the tension thereof, mechanism for imparting movement to said means, and means under control of the operating mechanism for indicating the tension of the spring under the influence of the movable means.

In testimony whereof I hereunto affix my signature in the presence of two witnesses.

GEORGE E. CUTLER.
